(57) **CLAIM**

The ornamental design for a rack having curved inset wheel connector, as shown and described.

DESCRIPTION

This application relates to Applicant's concurrently filed design application Ser. No. 29/175,572 entitled "Rack Having Inset Wheel".

FIG. 1 is a front perspective view of a rack having curved inset wheel connector according to my design;

FIG. 2 is a side view of my rack having curved inset wheel connector of FIG. 1;

FIG. 3 is a front view of a rack having curved inset wheel connector according to my design; and,

FIG. 4 is an enlarged view of a portion of my rack having curved inset wheel connector of FIG. 1.

The unillustrated views form no part of the claimed design. The broken line portions form no part of the claimed design.
